MEANS FOR FORMING SPACING BANDS

Frederick W. Burger, Niles, Mich., assignor to
 Clark Equipment Company, Buchanan, Mich.,
 a corporation of Michigan

Application November 25, 1938, Serial No. 242,167

1 Claim. (Cl. 153—3)

This invention relates to means for forming spacing bands of the type employed in dual wheel assemblies for spacing the tire carrying rims on opposite sides of a central radial abutment carried by the wheel spider.

The invention is particularly directed to means for forming spacing bands of the type shown in Burger patent, Reissue No. 19,885, dated March 10, 1936.

The present invention contemplates forming such bands from flat strip material by rolling the material into angle shape and then forcing the same through an arcuate die to produce the proper curvature therein for embracing the wheel spider.

One of the primary objects of the present invention is to form such bands more economically and at greater speed than it was possible heretofore.

Another feature of the present invention is in the use of flat strip stock, which can be purchased at low cost and which can be cut into the proper lengths so that as it is passed through the rolls and die member the band is accurately formed to proper shape and requires only a punch operation to form the locking means therein.

Still another feature of the present invention is the use of a roll member contacting the band as it leaves the arcuate die for imparting a slight amount of reverse bend thereto. This is of distinct importance as it relieves the strains produced in the strip as it is passed through the arcuate die in such manner that if the ring or band thus formed is accidentally dropped, it will have a tendency to contract in diameter rather than expand, whereas, if such reversing stress was not introduced into the band it might, through handling or the like, spring open to a position such as to render it difficult to latch it about the wheel spider.

The process is readily adaptable to forming bands of varying diameters by the substitution of arcuate die members having various radii of curvature. The reversing or blocking member is preferably adjustable so that it is capable of movement into the proper position, depending upon the type of curving die employed.

It is desirable that such spacing bands have suitable means for latching the ends together when placed on a wheel spider. To accomplish this purpose, the blanks are preferably cut to a length such that when rolled they will be of proper circumferential extent to embrace the wheel spider in the proper manner. Preferably, one end of each blank is notched to form the

latching tongue, and when the rolling operation and curving operation have been completed the band is placed on a suitable horn punch or the like and the latching tongue is bent to proper shape, then the latch notch is cut out from the opposite end of the band at a suitably gauged distance so as to produce the proper latching action.

If desired, the blank may be cut to exact length and notches punched in each end prior to passage through the rolls and curving die. In such case it is only necessary to bend the latch tongue into latching position in a subsequent forming operation in order to produce the completed band.

Other objects and advantages of the present invention will appear more fully from the following detailed description which, taken in conjunction with the accompanying drawings, will disclose to those skilled in the art the particular method and apparatus employed for forming bands of the type disclosed.

In the drawings:

Figure 1 is an elevational view showing the rolling and curving operations;

Figure 2 is a plan view of the flat blank prior to its entrance into the rolls;

Figure 3 is an end elevational view of the structure shown in Figure 1;

Figure 4 is a diagrammatic representation of the latch forming operation;

Figure 5 is a sectional view of the band as formed in the present invention taken substantially on line 5—5 of Figure 6;

Figure 6 is a plan view of the adjacent ends of the band with the latch formed therein;

Figure 7 is a side view of the structure shown in Figure 6 taken substantially along line 7—7 of Figure 6; and

Figure 8 is a plan view of a modified form of blank which may be employed in the present invention.

Considering now in detail the drawings, the blank 5 as shown in Figure 2 is formed of flat strip stock, preferably that known as SAE 1020, and has one end thereof notched as shown at 6. It will be noted that the notch 6 extends more than half way across the width of the blank and provides the extending tongue 7 for a purpose to be described in detail hereinafter.

The blank 5 after being cut to length and notched is adapted to be fed through a series of rolls 8, 9 and 10, wherein it is formed into an angle shaped section substantially as shown in Figure 5. The rolls 8 constitute feeding rolls for

feeding the blank into the rolls 9 and 10, which rolls are so formed as to bend up or flange the metal to provide the cylindrically flanged portion 12 and the radially extending flange 13 at one edge thereof, the two being joined by a slightly curved filleted portion 14 which adds rigidity to the flange 13 and is retained beneath the rim gutter in operation. The rolls 9 and 10 are preferably removable so as to accommodate the insertion of different rolls and different widths of band depending upon the particular type of wheel spider in which the band is to be used. From the roll 10 the flanged band passes into a guide 16 extending closely adjacent the outlet portion of the rolls 10. The guide 16 guides this band into the straight die 17 having an opening therein conforming in section to the section of the band shown in Figure 5. This serves to hold the band against buckling, and also guides the band into the opening 18 in the curving die member 19. This curving die member 19 has the opening 18 therein extending in a longitudinal arc predetermined in accordance with the desired diameter of the band. Preferably, the curvature of the opening 18 is such as to provide a slightly smaller band than that desired. For example, for a twenty inch wheel spider, the curvature of the die opening in the die 19 would be such as to bring the diameter of the band to a smaller diameter than twenty inches. However, such a band if the stresses were not relieved therein, would be susceptible to moving into a larger diameter during handling or the like, especially if dropped, due to the strains produced therein during the curving operation. In order to eliminate such a condition the blocking bar 20 is provided mounted on the base member 22 supporting the rolls and dies and having slots 23 therein accommodating slight longitudinal movement of the block 20 in a direction substantially normal to the travel of the band 5. The block 20 is adjusted in position by means of the adjusting screw 24 carried on the flange 25 of the stand, and preferably carries a roller 26 which is adapted to engage the under-surface of the cylindrical flange 12 of the band.

The member 20 is adjusted into such position that the band 5 is bent slightly in a reverse direction from the curvature produced in the die 19. This counteracts the stresses set up in the die 19 and imparts a sufficient reverse stress in the band 5 such that upon dropping or the like the band will tend to contract instead of expanding. It should be understood of course that the roller 26 does not impart such a reverse curvature to the band 5 as to distort it so that its diameter would exceed to any appreciable extent the proper diameter desired in the band for the particular wheel with which it is to be employed.

After the blank 5 leaves the roller 26 it is placed upon a suitable gauge block 28 where the opposite end 29 of the blank 5 is punched in a suitable manner to produce therein the recess 30 having the laterally projecting tongue 32 forming a latch recess in the cylindrical portion 12 of this end of the blank. The gauge block 28 is designed so that this punching operation will gauge the notch 30 with respect to the opposite end 33 of the blank a distance such that when in latched position the latch tongue will be more or less centered in the recess 30. The tongue 7 initially formed on the blank 5 before the rolling and curving operations is also

positioned on the gauge block 28 in such manner that when the punch 35 descends thereonto, it bends up the end 36 of this tongue and bends down an intermediate portion of the tongue, as indicated at 37, in suitable relationship to the gauge space 38 between the ends of the band. Thus, whether the band is slightly over length or not will have no effect upon the latching operation since it only means that the tongue 36 will project upwardly a slightly greater distance, which will not in any way affect the operation of the band in carrying out its proper functions in the wheel assembly.

The offset portion 37 of the tongue 7 is provided for the purpose of clearing the tongue 32 on the opposite end of the band to provide for proper latching cooperation between the tongue 7 and the latch recess 30. With the band in position on the wheel spider and embracing the spoke shoulders adjacent the central abutment, the latch should be formed in such manner that the tongue 37 is out of contact with either of the end surfaces of the recess 30, as shown in Figures 6 and 7; thereby allowing a certain amount of play in the band to accommodate manufacturing tolerances in the wheel spider; and also to facilitate easy application of the band to the spider.

In Figure 8 I have disclosed a modified form of blank 40 having a notch 42 formed at one end thereof to define the latch tongue 43 corresponding to the latch tongue 7 of Figure 2. However, the blank 40 of this modification is cut exactly to a predetermined length, depending upon the diameter of band required; and the opposite end of the band 44 thereof is notched as indicated at 45 to provide the latch recess having the tongue 46 corresponding to the tongue 32 of Figure 6. With such a construction the two ends of the band are preformed prior to the rolling and curving operation so that the only requirement upon completion of the curving operation is the bending of the tongue portion 43 to provide an offset portion corresponding to that indicated at 37 and a lip portion corresponding to that indicated at 36 in Figures 6 and 7.

It is therefore believed apparent that a simplified method of forming such bands is produced by following the process described, and that the apparatus for producing such bands is of simple and inexpensive character and is readily adjustable for forming various sizes of bands and does not require any appreciable outlay in tools or fixtures.

After the band has been formed it may be plated with cadmium or the like as a protection against rusting, or may be given a coating of prime paint as desired.

Due to the stress conditions in the band, handling of the bands will not produce enlargement thereof but will tend to contract the same slightly, which is desirable in order to make the band hug the wheel spider as closely as possible when in operating position.

I am aware that various changes may be made in certain details of the present invention without departing from the underlying principles thereof, and I therefore do not intend to be limited except as defined by the scope and spirit of the appended claim.

I claim:

Apparatus for forming an angle section circular spacing band from a flat blank comprising feeding and rolling means for forming said blank

into an angle shape, a first rigid die having a longitudinally extending die opening into which said blank is fed, a second rigid die having an arcuate die opening with the entrance end disposed closely adjacent to and aligned with the exit end of said first die for imparting a predetermined curvature to said blank as it is forced longitudinally therethrough, said first die serving

5 to support said blank against buckling and adjustable roller means contacting the inner annular surface of said blank as it leaves said second die for effecting a slight straightening of said blank to remove the stresses introduced therein in said arcuate die.

FREDERICK W. BURGER.
